G. CAVAGLIERI.
WINDOW SCREEN.
APPLICATION FILED JUNE 4, 1917.

1,260,641.

Patented Mar. 26, 1918.

UNITED STATES PATENT OFFICE.

GIUSEPPE CAVAGLIERI, OF LOS ANGELES, CALIFORNIA.

WINDOW-SCREEN.

1,260,641.

Specification of Letters Patent. Patented Mar. 26, 1918.

Application filed June 4, 1917. Serial No. 172,665.

To all whom it may concern:

Be it known that I, GIUSEPPE CAVAGLIERI, a citizen of the United States, residing at Los Angeles, in the county of Los Angeles and State of California, have invented new and useful Improvements in Window-Screens, of which the following is a specification.

This invention relates to a window construction and particularly pertains to a screen therefor.

It is the principal object of this invention to provide a window screen which may be easily positioned over a window opening and may be instantly removed from its obstructing position.

Another object of this invention is to provide a window screen which may be incorporated within the window frame structure and may be allowed to roll up within the frame, or be drawn therefrom to any desired length.

Another object of this invention is to provide simple means whereby access to the screen mounting may be obtained without dismantling the window frame and which will permit the screen fabric to be readily removed and replaced by another fabric, when desired.

30 It is a further object of this invention to provide a window screen of the above class requiring inexpensive and simple mountings and which will not interfere with the swinging movement of the casement windows upon which it is used.

Other objects will appear hereinafter.

The invention is illustrated, by way of example, in the accompanying drawings in which:

40 Figure 1 is a view in elevation illustrating a window frame with parts removed to particularly disclose the mounting of a window screen therein, said screen being constructed according to the spirit of the present invention.

Fig. 2 is an enlarged fragmentary view in elevation illustrating the window screen and disclosing in detail its mounting and counter-weights arrangement.

50 Fig. 3 is a view in vertical section and elevation as seen through the window frame with parts broken away for the sake of convenience, and clearly disclosing the relation of the screen thereto and the manner in which it may be detachably secured to its roller.

Fig. 4 is a view in transverse section as seen on the line 4-4 of Fig. 3 illustrating the relation of the screen to the window frame and its counter-weights. 60

Fig. 5 is a view in vertical section illustrating the window sill and particularly showing the lower portion of the screen as resting upon the sill when an inwardly swing window sash is used. 65

Fig. 6 is a view in vertical section similar to Fig. 5 illustrating the disposition of the screen when an outwardly swinging sash is used.

Fig. 7 is an enlarged view in section illustrating the lower marginal edge of the screen, and particularly disclosing the manner in which it is bound. 70

Referring more particularly to the drawings, 10 indicates a casement window sash 75 which is adapted to swing horizontally upon its hinges. This sash is pivotally secured within a window frame 11. This frame is formed with weight wells 12 and 13 extending parallel to each other and along opposite sides thereof. Counter-weights 14 and 15 are positioned within these wells and are suspended from the ends of cables 16 and 17. These cables are wound around the trunnions 18 and 19 of a window screen 85 roller 20. As particularly disclosed in Fig. 3 of the drawings, this roller is formed in two parts, a main portion 21 of which is semi-circular in section and is supplemented by a small semi-circular section around 90 which an arcuate clamping portion 22 is seated. This portion is held to the main part of the roller by means of screws 23 and is adapted to bind the end of a reticulated fabric 24 to the roller. This fabric is preferably formed of wire and is semi-flexible so that it may be wound around the roller. The fabric screen 24 is of a slightly greater width than the window opening and therefore is positioned within vertical slots 25, 100 which extend the length of the frame sides and hold the screen so that it will seal the opening. The lower edge of the screen is bound by a metal strip 26, particularly disclosed in Fig. 7 of the drawings. This strip 105 is folded twice and incloses the folded lower edge of the screen, thus securely holding the screen fabric and preventing it from loosening. Mounted on the back side of the binding strip 26 is a metal counterweight 27 110 which adds sufficient weight to the screen to counterbalance the weights 14 and 15. This

counterweight strip is secured to the metal binding strip 26 and a facing strip 27 by means of wood screws 34. The facing strip 27' is made of wood and finished to match the wood-work within the room. When the binding and facing strips are assembled, as shown in the drawings, the ends of the metal strip will extend outwardly and slide along the vertical slots 25 in the frame. The facing is formed with a recess 28 within which the fingers may be positioned and the screen raised and lowered. This facing is adapted to be drawn down to bear upon the window sill 29. When in this position the window opening will be closed by the screen.

It will be understood that the casement windows may be designed to swing either inwardly, or outwardly. In Fig. 5 the window is shown as swinging inwardly, while in Fig. 6 the window swings outwardly. In either case the operation of the screen will be the same.

In order that the screen may be easily renewed, or removed, if desired, a removable head board 30 is positioned at the top of the frame and secured in place by two angle members 31 and 32. This board forms a slotted opening 33 through which the screen may pass and, when removed, allows the screws 23 to be withdrawn from the roller. This will allow the removal of the clamping portions 22 of the roller and permit the screen fabric to be drawn therefrom.

When this device is used, the binding edge of the screen may be grasped and drawn down. This will unroll the screen from the roller against the action of the counterweights 14 and 15, and will permit the screen to stand at rest when it has been sufficiently drawn. In case the use of the screen is not desired, it may be raised and will automatically be wound upon the roller 21 as the counterweights are lowered within their wells. If the screen is to be removed the head board 30 is taken out of its position and the roller parted, as previously described. The screen may be removed from the binding strip by loosening

the screws 34 to separate the counterweight strip 27 and the facing strip 27', after which the metal binding strip 26 may be sprung from the vertical slots 25 and slipped endwise from the screen. A reversal of this operation will rebind the screen and remount it upon its roller.

It will thus be seen that the screen here disclosed is simple in its construction, does not require special mounting members, and may be easily drawn into a closing position over a window opening, or may be raised out of the way, and furthermore may be easily renewed, when desired, without dismantling the entire window frame.

While I have shown the preferred construction of my window screen as now known to me, it will be understood that various changes in the combination, construction and arrangement of parts may be made by those skilled in the art without departing from the spirit of my invention.

I claim:

In a window screen, the combination with a window frame, of a screen roller positioned within said frame and at the upper end thereof, a flexible screen fabric detachably secured to said roller; said frame having a slotted opening through which the roller is mounted upon its support; a removable closure member adapted to partially obstruct said opening and to provide a passage-way through which the screen may travel, guide grooves formed along the opposite sides of the frame opening within which the edges of the screen move, a counterweight strip fastened along the lower edge of the screen, a facing strip upon the opposite side of the screen and to which the counterweight strip is secured, cables wound around the ends of the screen roller, and counterweights secured to the ends of the cables to counterbalance the counterweight strip and the screen.

In testimony whereof I have signed my name to this specification.

GIUSEPPE CAVAGLIERI.
